SAFETY RAZOR

Application filed April 22, 1931. Serial No. 532,100.

This invention relates to safety razors and more particularly to a safety razor by the use of which hair may be shaved from under a person's arm without danger of cutting.

5 Razors of the type used for shaving a person's face have been found unsatisfactory when shaving hair under a person's arms as the blade and its holder have straight edges and since the arm pit is hollow and an arm 10 must be held in a raised position during a shaving operation, a razor having a straight cutting edge will not fit properly into an arm pit and very often a person will be cut by an end portion of a blade.

15 Therefore one object of the invention is to provide a razor having its blade and the portions of the razor between which the blade is secured, so shaped that when the razor is in use it will fit properly into the hollow under 20 a person's arm and hair may be shaved from the same without danger of cutting.

Another object of the invention is to provide the razor with blade engaging portions so constructed that the razor may be easily 25 assembled, and when assembled the blade and its guard firmly secured and prevented from slipping out of its proper position.

Another object of the invention is to provide the razor without a handle curved longitudinally so that when the razor is in use, it 30 may be easily held and its blade disposed in proper engagement with a person's arm during a shaving operation.

Another object of the invention is to provide a razor which is very simple in construction and strong and durable.

The invention is illustrated in the accompanying drawing, wherein:

Figure 1 is a perspective view of the improved razor.

Figure 2 is a sectional view through the razor taken along the line 2-2 of Figure 1,

Figure 3 is a view showing the upper portion of the razor in section along the line 45 3-3 of Figure 2,

Figure 4 is a view similar to Figure 2 with the blade and its guard removed, and

Figure 5 is a view of the razor blade.

The handle 1 of this razor may be of any 50 length and thickness desired and will pref-

erably be circular in cross section. The handle curves longitudinally and has its upper end flattened and bent to form an arm 2 which projects forwardly from the handle and carries a head or jaw 3 which extends downwardly from the arm in front of the handle in spaced relation thereto as clearly shown in Figure 3.

The lower edge 4 of this head or jaw 3 is arcuate and is preferably a semi-circle with its ends intersecting the upper edge of the head but it will be understood that the arcuate lower edge of the head may constitute any portion of a circle desired. Lugs 5 project rearwardly from the head at opposite sides 60 thereof slightly below its upper edge as clearly shown in Figures 1, 2, and 4 and have their outer side edge faces flush with the arcuate edge face of the head.

A blade 6 fits against the rear face of the 70 head or jaw 3 and this blade has a sharpened arcuate lower edge 7 and has its end portions shaped as clearly shown in Figure 5 to form recesses or seats 8 and arms 9 which are so located that when the blade is set in place 75 against the rear face of the head 3 the lugs 5 will project rearwardly through the recesses 8 and the arms 9 engage over the lugs. Therefore the blade will be retained in its proper position against the head with its sharpened 80 lower edge 7 projecting a slight distance beyond the arcuate edge of the head. A guard 10 which conforms to the shape of the blade

6 fits against the rear face of the blade and is formed with recesses 11 through which the 85 lugs 5 project, and also formed with arms 12 extending across the upper edge faces of the lugs. The lower edge portion of the guard is bowed rearwardly as shown at 13 thereby providing the guard or jaw 10 with a 90 curved portion disposed in shielding relation to the sharpened edge of the blade as shown in Figure 3 and permitting the razor to be applied beneath a person's arm and then tilted into proper position for shaving without danger of a person being cut when the 95 razor is initially disposed in position for use.

In order to retain the blade and guard firmly in engagement with the head or jaw 3 100

there has been provided a set screw 14 which passes through a threaded opening 15 and has its forward end bearing against a thickened portion or block 16 formed substantially in the center of the rear face of the guard. This reinforces the portion of the guard against which the set screw engages and therefore the set screw may be tightened to firmly hold the guard and blade in place 10 without danger of pressure exerted by the screw cracking the guard or quickly wearing a hole at the point where it bears against the guard.

When this razor is in use, the blade is fitted 15 against the rear face of the head 3 and the guard then set in place. After the blade and guard have been applied with the lugs 5 projecting rearwardly through the recesses in the blade and guard to retain them in proper relation to the head the set screw is rotated by 20 grasping the head 17 at its rear end in order to move the forward end of the set screw into contact with the block 16. The set screw may then be tightened and the blade and guard 25 will be firmly held in place. The razor is then held by its handle and since the handle is curved longitudinally and the cutting edge of the blade and adjacent edges of the guard and head are arcuate, the razor may be applied beneath a person's arm and hair removed without danger of cutting.

After the shaving operation is completed 30 the set screw is loosened and the guard and blade can then be removed and after being washed and dried the razor again assembled or put away without being assembled until again needed.

What is claimed is:

A razor comprising a handle having its 40 upper end reduced to form an overhanging arm terminating in a depending head, the inner face of the arm and the inner face of the head being disposed at right angles to each other and said inner face of the head being arranged substantially parallel with the adjacent portion of the handle, said head being provided with an arcuate lower edge and having lugs projecting inwardly therefrom on opposite sides of the arm, a blade fitting 50 against the inner side of the head and having its upper edge bearing against the inner face of the overhanging arm and its lower edge curved to conform to the arcuate lower edge of said head, said blade being provided with recesses adapted to receive the lugs, a guard fitting against the blade and having its lower edge of arcuate formation and bowed rearwardly to overhang the adjacent edge of the blade, said guard being provided with recesses fitting the lugs on the head, the outer surface of the guard being provided with a reinforcement, and a clamping screw threaded in the handle near said arm and having one end thereof bearing against the reinforcement and its other end provided with a finger

piece for turning the fastening device to cause the same to frictionally engage the enlargement and retain the blade and guard in position on the head.

In testimony whereof I affix my signature. 70
